SIGNORS TO THE P. H. & F. M. ROOTS COMPANY, OF CONNERSVILLE, INDIANA.

FLUID-PRESSURE GOVERNOR.

973,197.

Specification of Letters Patent. Patented Oct. 18, 1910.

Application filed June 15, 1910. Serial No. 566,913.

To all whom it may concern:

Be it known that we, GEORGE C. HICKS, Jr., and RALPH C. ENYART, citizens of the United States, residing at Connersville, 5 Fayette county, Indiana, have invented certain new and useful Improvements in Fluid-Pressure Governors, of which the following is a specification.

This invention relates to a governor for maintaining a practically constant pressure of fluid by causing variations in the produced pressure to modify the speed of the motor bringing about the production of the pressure. Such governors, as a class, are 10 not new; but cases arise in which considerable power is required in bringing about the speed-adjustment of the motor, as for instance, where a pressure-producing machine is driven by a steam engine having a 15 variable cutoff of the riding valve type, and our present invention well lends itself to the adjustment of such cutoff valves, or to similar situations.

The invention will be readily understood 20 from the following description taken in connection with the accompanying drawing which is a vertical section of a governor exemplifying our invention.

In the drawing:—1, indicates a pipe or 25 receiver containing, under pressure, the fluid to be dealt with, which may be assumed as air, the pressure within this pipe representing the pressure which is to be kept constant or practically so: 2, a rotary shaft typical of a mechanical part whose turnings, in one direction or the other, are to bring about corrective adjustments of the 30 motor which is producing the pressure as, for instance, the valve-gear of a steam engine driving a blower, shaft 2 being illustrated in the present case as having a crank 35 upon it: 3, a connecting rod attached to crank 7 and serving simply to typify another mechanical means for carrying motion 40 away from shaft 2 to bring about a speed adjustment of a motor: 4, a rotary motor, adapted to be driven in either direction by the pressure fluid, the motor being illustrated as having two impellers working in 45 a casing, like the well known Roots type of rotary blowers: 5, a passage leading into one side of the casing of the blower and serving, according to circumstances, as an inlet or 50 an outlet for the pressure fluid: 6, a similar passage connecting with the opposite side

of the casing of the motor, these two passages terminating at points near each other: 7, the crank previously referred to, which crank is a gear engaging a pinion on the shaft of one of the impellers so that the 55 turning of the impellers brings about the turning of shaft 2: 8, a supply conduit leading from pressure-pipe 1 to a point near the ends of passages 5 and 6: 9, an exhaust conduit leading from a point near the ends of 60 passages 5 and 6: 10, a valve coöperating with passages 5 and 6 and supply-conduit 8 and exhaust conduit 9 in such manner that when the valve is in one position, the position shown in the drawing, no fluid will go 65 to the motor 4 and, when in another position, fluid will go to passage 5 while passage 6 will be in communication with the exhaust and, in another position, fluid will go to 70 passage 6 while passage 5 will be in communication with the exhaust, as will be obvious from an inspection of the drawing: 11, a diaphragm chamber: 12, a flexible diaphragm forming a wall of this chamber: 13, a conduit leading from pressure-pipe 1 to the 75 diaphragm chamber and tending to distend the diaphragm: 14, a lever: 15, a connection from the lever to the diaphragm to cause variations in the distention of the diaphragm to 80 bring about variations in the position of the lever: 16, a lever connected with valve 10 to serve in shifting that valve to its various functional positions: 17, a link connecting levers 14 and 16, this link being illustrated as being provided with a turnbuckle to serve 85 in adjusting its length: 18, a spring connected with lever 14 and tending to resist the distention of the diaphragm under the influence of the pressure acting upon it: and 90 19, an adjusting screw for changing the tension of the spring. 95

Assume the system with which this invention is to be employed to be working under some given pressure which it is desired to hold constant. That pressure will be acting 100 upon diaphragm 12, and spring 18 is to be so adjusted as to put lever 14 in condition of equilibrium with valve 10 in completely closed position. Under these conditions the governor will not be performing any duty, 105 but will stand ready for duty. If, now, the pressure in the system rises above the normal it will bring about an increased distention of the diaphragm, and this will obviously result in so shifting valve 10 that pressure. 110

2

fluid will go through passage 6 to the motor, causing the rotation of the motor, the fluid exhausting from the motor through passage 5. The turning of the motor brings about a turning of shaft 2 or movement of connection 3 to effect a proper speed correction of the engine supplying the system with pressure fluid, such speed correction slowing the engine and causing the pressure in the system to get back to normal, whereupon the diaphragm takes its original position, closing valve 10 and stopping the motor. If, on the other hand, the pressure in the system should fall below the normal, then spring 18 will have a preponderating effect over diaphragm 12 and the distention of the diaphragm will lessen, and the valve will go to a position causing the motor to turn in a direction opposite to the direction previously referred to, and bring about an adjustment to quicken the speed of the engine producing the pressure, the governor-motor ceasing to operate when the pressure shall have been restored to normal.

25. We claim:—
 1. A fluid-pressure governor comprising, a reversible rotary governor-motor adapted for the adjustment of the speed-controlling part of a pressure-producing motor, a reversing valve for said governor-motor, a chamber, a movable wall to said chamber, an adjustable resistance connected with said wall, a connection between said wall and valve, a

conduit to supply said chamber with fluid at working pressure of the system, and a supply conduit to convey fluid to the reversing valve, combined substantially as set forth. 35

2. A fluid pressure governor comprising, a rotary governor-motor adapted for rotation in either direction, a part driven thereby and adapted for connection with a pressure-producing motor, a pipe charged with the pressure-fluid whose pressure is to be governed, passages connected with the governor-motor, an exhaust outlet for the governor-motor, a supply-conduit from said pipe to the motor, a valve coöperating with said supply conduit and passages and exhaust outlet to bring about the turning of the governor-motor in one direction or the other, a diaphragm chamber connected with the first-mentioned pipe, a diaphragm forming a wall of said chamber and held under distention by the working pressure of the system, an adjustable spring resisting the distention of the diaphragm, and connections from the diaphragm to the valve to cause abnormal distentions of the diaphragm to bring about the turning of the governor-motor in one direction or the other, combined substantially as set forth. 45 50 55 60
